UNITED STATES PATENT OFFICE.

SAMUEL G. SALKA, OF CHICAGO, ILLINOIS.

MUFFLER.

1,153,260.

Specification of Letters Patent. Patented Sept. 14, 1915.

Application filed January 23, 1915. Serial No. 3,852.

To all whom it may concern:

Be it known that I, SAMUEL G. SALKA, a subject of the Czar of Russia, residing at Chicago, in the county of Cook and State 5 of Illinois, have invented certain new and useful Improvements in Mufflers, of which the following is a specification.

This invention relates to mufflers which may be worn upon the interior or exterior 10 of a coat and in the latter event, may comprise an ornamental collar for the coat.

It is the object of the present device to combine in one article, a chest and throat 15 protector, with an ear muffler which may or may not be attached to the coat of the wearer and which, in any event, will present a smooth finished appearance.

With the above and other objects in view, this invention consists in the construction, 20 combination, and arrangement of parts, all as hereinafter more fully described, claimed, and illustrated in the accompanying drawings wherein:—

Figure 1 is an elevation of the present 25 invention in its operative position in conjunction with a wearer; Fig. 2 is a similar view with the muffler lowered in position to act as a collar for coat; and Fig. 3 is a plan or pattern view of the device.

Reference being had more particularly to 30 the drawings, 10 designates the body of the muffler forming the subject matter of the present invention, which is provided along its outer edge with concave 11, and along 35 its inner edge with the curve 12. This body portion 10 of the muffler embraces the neck of the wearer by means of the curved edge 12, and when elevated to cover and protect the ears of the wearer the concaved edge 11 40 accommodates and conforms to the contour of the head of the wearer.

At each end of the body portion 10 and extending from the edge 12 thereof is a flap or extension 13. The outer edges 14 of 45 these extensions or flaps 13 are approximately straight, while the inner edges 15 thereof are curved to form continuations of the curved edge 12 of the body portion 10 so that the muffler when in use either elevated or lowered will conform to the contour of the body of the wearer, as clearly illustrated in both Figs. 1 and 2.

When the muffler is elevated for the protection of the ears and throat, it is essential 50 that it be so formed as to accommodate the face of the wearer, leaving the

mouth and nostrils free from obstruction; while, when the muffler is lowered, as in Fig. 2, it should conform to the curve of the shoulders of the wearer. For this purpose the outer edge 14 of each flap or extension 13 terminates in a curved edge 16 which connects the edge 14 with the end edge 17 of the body portion 10. Thus, when the muffler is elevated the curved edges 16 60 rest under the chin of the wearer while the edges 17 rest against his cheeks; whereas when lowered, as in Fig. 2, the curved edges 16 are located on the shoulders of the wearer. 65

The body portion is provided with the divergent seams 18 for bracing and supporting purposes. At the points where the body portion contacts with the ears of the wearer, it is stitched as at 19 to create a 70 75 form or depression in which each ear is received.

In order to maintain the muffler in its elevated position, an elastic band 20 spans the concave 11 from one side thereof to the 80 other, and when the body portion 10 is in the position shown in Fig. 1, the band 20 passes over the head of the wearer under the hat and retains the body portion 10 in the illustrated position. 85

Snap catches 21 are provided along the edges 14, so that when the muffler is in its 90 operative position, the edges 14 may be secured together thereby protecting the throat and chest.

When the muffler is worn on the exterior 95 of the coat, the outer surface thereof, referring to Fig. 2, may be covered with fur or other decorative material, and the ends of the flaps or extensions 13 may be bent under the lapels of the coat, as at 22, and secured there by suitable snap catches 23.

While the preferred form of the present invention is shown and described, it is to be understood that many changes may be 100 made in the details of construction without departing from the spirit and scope hereof.

What is claimed is:

A device of the class described comprising 105 a middle portion having a concaved outer edge and rounded outer end corners and two end portions extending in approximate parallelism and at a right angle from the opposite ends of the middle portion, 110 said end portions having curved inner and outer side edges and straight end edges, a

head band having its opposite ends fastened to the rounded outer end corners of the middle portion, and a series of fasteners attached to the opposite end portions and 5 arranged at intervals along the straight end edges thereof; said device being adapted to be fitted in folded position upon the coat of the wearer or with the middle portion turned up over the ears and back of the 10 head, the head band passed over the head

and the straight margins of the end portions lapped upon the chest and secured by the fasteners.

In testimony whereof I have hereunto affixed my name in the presence of two wit- 15 nesses.

SAMUEL G. SALKA.
